UNITED STATES PATENT OFFICE.

ADOLPH OUSDAHL, OF SEATTLE, WASHINGTON.

AUTOMATIC STOKER.

Application filed November 27, 1920. Serial No. 426,735.

To all whom it may concern:

Be it known that I, ADOLPH OUSDAHL, a citizen of the United States, and resident of the city of Seattle, in the county of King and State of Washington, have invented certain new and useful Improvements in Automatic Stokers, of which the following is a specification.

My invention relates to automatic stokers 10 and comprises particularly means for controlling such stokers.

The general object of my invention is to provide means which will regulate such stokers either directly or indirectly through 15 the heat of the furnace fed by the stoker, or of the building heated thereby, to maintain an even temperature.

In connection with this general object it is my object to provide a fuel feed device 20 and an automatically variable drive mechanism therefor.

It is another object of my invention to provide heat-controlled means for automatically stopping the driving motor or for 25 starting it again, between predetermined temperature limits, which means may be regulated to vary the temperature limits.

Another object is to provide means for regulating and controlling the draft to the 30 furnace in accordance with the temperature which it is desired to maintain.

Another object is to provide a driving 35 means for automatic stokers which will be silent and yet effective in operation.

Another object of my invention is to provide means, in connection with automatic stokers employing a feed hopper, for agitating the fuel therein and for urging it toward the delivery opening of the hopper.

Other objects may be ascertained by a 40 study of the following description and claims.

In the accompanying drawings I have shown my invention in a form which is now 45 preferred by me.

Figure 1 is an elevation of my stoker, parts being broken away.

Figure 2 is an elevation of the stoker from 50 the opposite side, parts being shown in section.

Figure 3 is a section through my device taken approximately upon the line of the main bearings.

Figure 4 is a section on line 4—4 of Figure 55 1 illustrating the main reduction gearing.

Figure 5 is an elevation of the variable drive mechanism.

Figure 6 is a diagram of a slightly different control means.

Figure 7 is an elevation of a heat-control 60 device which I prefer to employ.

Essentially my stoker, in common with many others, includes a piston 1 reciprocable within a cylinder 10 by suitable driving mechanism. At one side the cylinder is open 65 to a suitable storage bin or hopper 11 which contains the fuel supply, and at one end it is open toward the furnace, into which the fuel is forced through the opening 12 by the piston 1. A connecting rod 13 connects the 70 piston 1 with a crank 14 which forms part of or which is secured upon the shaft 15.

The driven gear 16 is preferably connected to a boss or collar 17 keyed upon the shaft 15 by means of a shear pin 18, although this 75 shear pin connection may be omitted if desired and the gear 16 may then be keyed directly upon the shaft 15. This gear is connected through a variable speed mechanism, designated in general by the numeral 80 2, and which is driven through an oscillating shaft 20 and through suitable reduction gearing to a suitable motor 3. This gearing designated in general by the numeral 30, and illustrated in detail in Figure 4, comprises 85

a pinion 30^a keyed to the same shaft as the pulley 30^b over which the belt 31 from the motor 3 passes; a gear 30^c with which the pinion 30^a meshes; a pinion 30^d on the same shaft as gear 30^c, meshing with a gear 30^e, 90 upon whose shaft is secured the crank arm 32, whereby the crank arm is slowly rotated. This rotating crank 32, which is driven from the motor 3 through the gearing 30, is connected to a crank arm 33 on the oscillating 95 shaft 20, by means of a link 34. The length of the crank arm 33 being greater than the length of the arm 32, the former crank arm 33 will be oscillated by the rotation of the latter crank arm 32. While this is my preferred driving connection, it is evident that any other suitable form may be employed and I do not desire to limit myself to the exact construction described, my purpose being only to secure continuous oscillation 105 of the crank arm 33.

The variable speed mechanism which I have shown and which I prefer to employ includes a ratchet wheel 21 and a dog 22 adapted to mesh therewith. The dog 22 is 110

carried upon the end of a crank 23 which is secured upon the shaft 20 and which is continuously oscillated thereby. Oscillation of the arm 23 would cause the dog 22 to engage with the wheel 21 at each stroke and to advance the wheel an amount equal to its stroke, if there were nothing to vary the engagement of the dog and wheel.

However, in order to vary the engagement of these two ratchet members, I employ a shield which may be positioned to intercept the dog 22 for a portion of its stroke. This shield is shown herein as a segment disk 24 of slightly greater radius than the ratchet wheel 21 and positioned closely alongside of the ratchet wheel. The ratchet wheel is freely rotatable upon the shaft 20 and is connected to a gear 25 meshing with the driven gear 16. The shield 24 is freely rotatable, preferably concentric with the ratchet wheel 21, and its periphery is movable into and out of the path of the dog 22. It may be positioned to intercept the engagement of the dog with the ratchet wheel during any portion of its stroke from no engagement up to engagement during the full stroke.

This is done by oscillating the shield 24 to bring more or less of its periphery within the path of movement of the dog 22. It is obvious, as may be seen in Figure 5, that when the shield 24 is in the path of movement of the dog 22 the latter may not engage the ratchet wheel until its stroke has carried it beyond the forward edge of the shield, as may be seen in dotted lines in the figure referred to. The oscillation of the shield 24 is accomplished in some suitable manner, as through an arm 26 connected thereto and oscillated by a control means to be described later.

In order to cause the ratchet device to operate silently, I provide in a boss 27 forming a part of the ratchet dog 22, a small spring-pressed plunger 28 projecting approximately radially inward. The plunger 28 is positioned to contact always with a continuous ring 29 mounted concentrically upon the shaft 20. During the drive stroke of the dog 22 the slight friction between the plunger 28 and the periphery of the ring 29 causes the dog 22 to be thrown forward into position to engage with the ratchet wheel 21, except as it may be intercepted by the shield 24. At the beginning of the reverse stroke of the dog, the friction of the plunger 28 and ring 29 causes the dog to be rocked upon its pivot so that it lifts directly upward out of engagement with the wheel 21 and is carried back to the beginning of its stroke in this position, owing to the friction between the plunger and ring referred to.

To assist in the combustion in the furnace I may provide a draft fan or blower, this being shown as mounted within the casing 4

and rotatable directly upon the motor shaft. Air is delivered through a duct 40, and at a suitable point a damper 41 is positioned, which may be turned to control or cut off the air delivered to the furnace.

The control means for my stoker may be any that are found suitable. These should be operable through the temperature of the building heated by the furnace. As one means of accomplishing this control indirectly through the building temperature, I have illustrated a metallic steam bellows 5 which is connected through a pipe 50 with steam delivered to the heating coils of the building. The volume of the steam expands directly as its temperature increases. Expansion of the steam within the bellows 5, due to increase in temperature, causes the tilting of a lever 51 pivoted at 52 in the frame surrounding the bellows 5 and fulcrumed directly upon the bellows at 53. As the specific form of this control forms no part of my invention, it is not believed to be necessary to describe it more fully.

Control links 54 and 55 depend from opposite ends of the lever 51. One of these links, as 54, may be connected through a suitable arm 45 to operate the damper 41 controlling the draft. The other link, as 55, may be connected through a bell crank lever 56 and link 57, or other suitable means, to oscillate the arm 26 controlling the variable feed device. Either one of these links 54 or 55, herein shown as the link 54, may be connected to a motor cut out device 6 which controls the starting and stopping of the motor 3, through a suitable connection, as collars 58 adjustably positioned thereupon and operating a bell crank lever 59, which is in turn connected to portions of the cut out device 6.

The cut out device 6 shown consists essentially of a circuit breaker switch of any ordinary type. That shown in Figure 2 consists briefly in a solenoid 60 operable to make or break both the main line switch 61 and the switch 62. A second switch 63 is connected by a link 64 to be operated by the bell crank lever 59. In the position shown in Figure 2 the main line through the leads 65 is open. Contact of the switch arm 63 with the opposite one of the terminals shown, completes the circuit through the solenoid and through the switch member 62 to again close the main line switch 61 and to start the operation of the motor. This is accomplished by contact of the upper of the collars 58 with the bell crank lever 59 and occurs when the temperature of the building is lowered. The reverse operation is identical, and occurs when the temperature becomes too great. A line-switch 66 may be employed in addition to that already described.

In figure 6 I have illustrated a thermo-

static control means whereby a thermostatic bar 68, which may be placed directly in the room the temperature of which it is desired to control, will operate the solenoid 60 in the manner described. In effect the thermostatic bar 68 takes the place of the switch arm 63. A transformer 69 may be employed to energize the thermostatic control circuit.

To agitate the fuel in the hopper 11 I may provide a rod 7 which is reciprocable therein near its inclined bottom and which carries agitators 70, so shaped as to force the coal downward toward the delivery opening. Reciprocation of the rod 7 may be accomplished by any suitable means, such as the lever 71 to which it is connected by a link 74, and which is oscillated from a connection upon the boss 17 through a long link 72, the lever 71 being longer than the length of the crank upon the boss 17. I may also secure a similar rod 73 to the lower part of the piston 1, extending through the delivery opening, this being provided with agitators or pushers 70.

25 An alarm mechanism may be employed in connection with the shear pin 18 for sounding an alarm bell 8 in case extraordinary resistance is encountered in the mechanism, such as will cause the fracture of the shear pin. This is shown herein as consisting of a contact point 81 secured in the boss 17 and a contact plate 82 secured upon and insulated from the gear 16 and normally out of contact with the point 81. 30 The plate 82 is connected to a ring 83 with which a brush 84 continuously contacts and the circuit leads thence to a bell 8 or other alarm device. The return circuit is through the battery 85 and the frame of the stoker. 40 Upon breakage of the driving connection between the boss 17 and the gear 16, continued rotation of the gear will bring the contact plate 82 into contact with the point 81 and will cause the sounding of the alarm, indicating that breakage has occurred. All fuel-forcing members are immediately held stationary, due to the failure of their drive connection.

50 In ordinary operation the constant speed motor 3 causes reciprocation of the piston 1, through the belt 31, the gears 30, and the variable speed ratchet device 2. The motor also drives the fan within the casing 4 at a constant speed. The agitators 70 are reciprocated from the motor through the variable speed mechanism 2.

55 The action of these various mechanisms is controlled from the thermostat 5. As the temperature increases the links 57 and 55 are actuated thereby to move the shield 24 to shield more of the teeth of the ratchet wheel 21 from the constant speed, regularly oscillating dog 22. In this manner the movement of the piston 1 and of the agi-

tators 70 is reduced. Movement of the link 54 at the same time causes movement of the draft damper 41 in the direction to close it. The fuel feed and draft are thus automatically and thermostatically reduced upon rise of temperature, and the reverse is true with a fall in temperature.

Ordinarily the emergency control collars 58 are not brought into operation, but if the usual thermostatic control proves insufficient to cause the desired change in temperature through regulation of the feeds, these emergency means are relied upon. In Figure 2, the temperature had risen sufficiently to shut off the motor by contact of the lower collar 58 with the lever 59, and in the position of parts shown the upper collar 58 is about to contact with the lever 59 again to start the motor, the temperature having now fallen.

Proper care in designing the machine for the fuel to be employed will practically eliminate the necessity for an emergency control, as the stoker will regulate itself for any or all temperatures, without supervision. It is unnecessary to set limits manually between which the stoker has free range, for it automatically responds to all temperature changes.

What I claim as my invention is:

1. In a stoker, a variable feed mechanism including an oscillating arm, a ratchet wheel mounted concentrically therewith, a dog carried by said arm and engageable with said ratchet wheel, and means for depressing said dog into engagement at the start 95 of a stroke and for raising it from engagement at the end thereof.

2. In a stoker, a variable feed mechanism including an oscillating arm, a ratchet wheel mounted concentrically therewith, a dog carried by said arm and engageable with said ratchet wheel, a ring mounted adjacent to and concentric with said wheels, and a spring-pressed plunger mounted in said dog 100 and engageable with said ring, as and for the purpose described.

3. In a stoker, in combination, a hopper having a slanting bottom, a motor positioned beneath said slanting bottom, a cylinder extending lengthwise of and below said hopper, and communicating therewith, a plunger reciprocable in said cylinder, a crank shaft operatively connected to said plunger, an oscillable countershaft extending parallel to said crank shaft and a crank arm thereon, ratchet driving means connecting said two shafts, a crank arm rotatable from said motor and positioned at one side of said hopper, and a link connecting said two cranks.

Signed at Seattle, King County, Washington, this 20th day of November, 1920.

ADOLPH OUSDAHL.
